Primary Examiner — Ian Simmons*Assistant Examiner* — Yolanda Robinson(74) *Attorney, Agent, or Firm* — Michael Best & Friedrich LLP(57) **CLAIM**

We claim the ornamental design for a lock, as shown and described.

DESCRIPTION

FIG. 1 is a perspective view of a lock embodying the invention.

FIG. 2 is a first end view of the lock shown in FIG. 1.

FIG. 3 is a second end view of the lock shown in FIG. 1.

FIG. 4 is a first side view of the lock shown in FIG. 1.

FIG. 5 is a second side view of the lock shown in FIG. 1.

FIG. 6 is a third side view of the lock shown in FIG. 1; and, FIG. 7 is a fourth side view of the lock shown in FIG. 1. The broken lines in FIG. 1-7 show portions of the lock that form no part of the claimed design.
